(57) **CLAIM**

The ornamental design for a mount for electronic display, as shown and described.

DESCRIPTION

FIG. 1 is a front perspective view of a mount for electronic display according to a first embodiment of the invention;

FIG. 2 is a front elevation view of the mount for electronic display depicted in FIG. 1;

FIG. 3 is a left side elevation view of the mount for electronic display depicted in FIG. 1;

FIG. 4 is a right side elevation view of the mount for electronic display depicted in FIG. 1;

FIG. 5 is a top plan view of the mount for electronic display depicted in FIG. 1; and,

FIG. 6 is a bottom plan view of the mount for electronic display depicted in FIG. 1.

The backside of the mount for electronic display is not claimed, and therefore is not shown.
